(57) **CLAIM**

We claim the ornamental design for a monitor stand, as shown and described.

DESCRIPTION

FIG. 1 is a perspective view of a monitor stand embodying the invention.

FIG. 2 is a front view of the monitor stand of FIG. 1.

FIG. 3 is a rear view of the monitor stand of FIG. 1.

FIG. 4 is a right side elevation view of the monitor stand of FIG. 1;

FIG. 5 is a left side elevation view of the monitor stand of FIG. 1;

FIG. 6 is a top plan view of the monitor stand of FIG. 1; and, FIG. 7 is a bottom plan view of the monitor stand of FIG. 1. The evenly-spaced broken lines shown in FIGS. 1-7 illustrate portions of the monitor stand that form no part of the claimed design. The dash-dot broken lines in FIGS. 1 and 4-7 illustrate the boundary of the claimed design that forms no part thereof.
